UNITED STATES PATENT OFFICE

DONALD R. DOHNER, OF PITTSBURGH, PENNSYLVANIA, ASSIGNOR TO WESTINGHOUSE ELECTRIC & MANUFACTURING COMPANY, A CORPORATION OF PENNSYLVANIA

DESIGN FOR A REFRIGERATOR CABINET

Application filed January 19, 1932. Serial No. 42,542. Term of patent 7 years.

To all whom it may concern:

Be it known that I, DONALD R. DOHNER, a citizen of the United States, residing at Pittsburgh, in the county of Allegheny and State of Pennsylvania, have invented a new, original, and ornamental Design for a Refrigerator Cabinet, of which the following is a specification, reference being had to the accompanying drawings, constituting a part hereof.

Fig. 1 is a front elevational view of a refrigerator cabinet showing an embodiment of my new design;

Fig. 2 is a side elevational view of the refrigerator cabinet shown in Fig. 1; and,

Fig. 3 is a top plan view of the refrigerator cabinet shown in Figs. 1 and 2.

I claim:

The ornamental design for a refrigerator cabinet substantially as shown.

In testimony whereof, I have hereunto subscribed my name this fifth day of January, 1932.

DONALD R. DOHNER.
